Patented Nov. 22, 1898.

M. LEITCH.
STEAM HEATING APPARATUS.

(Application filed June 3, 1897.)

(No Model.)

UNITED STATES PATENT OFFICE.

MEREDITH LEITCH, OF MERCHANTVILLE, NEW JERSEY, ASSIGNOR TO THE WARREN WEBSTER & COMPANY, OF NEW JERSEY.

STEAM HEATING APPARATUS.

SPECIFICATION forming part of Letters Patent No. 614,658, dated November 22, 1898.

Application filed June 3, 1897. Serial No. 639,203. (No model.)

To all whom it may concern:

Be it known that I, MEREDITH LEITCH, of Merchantville, Camden county, State of New Jersey, have invented an Improvement in 5 Steam Heating Apparatus, of which the following is a specification.

My invention relates to steam heating apparatus; and it consists of the improvements which are fully described in the following 10 specification and shown in the accompanying drawings.

It is greatly desired that the temperature of steam-radiators should be subject to control, as the amount of heat desired varies 15 with the conditions, such as the state of the weather, as well as with the temperament and physical condition of the occupants of the room or house. In an office-building or hotel the amount of heat desired by some tenants 20 or guests differs greatly from that desired by others; but as the conditions under which the heat is supplied are usually uniform it is not practical to regulate the temperature to suit these various desires.

25 It is the object of this invention to enable the temperature of a steam-radiator to be controlled to suit the desires of the occupants of the room, and as the temperature depends upon the volume of steam condensed I accomplish this object by controlling the amount 30 of steam condensed in the radiator.

My invention is especially adapted to a "one-pipe" system, or one in which a single pipe is employed for supplying steam to the 35 radiator and conveying the water of condensation therefrom, and may be used either with a pressure system in which the air is permitted to escape from the radiator or with a system in which the air is exhausted or drawn 40 off from the radiator by a partial vacuum in an air-pipe communicating therewith.

In carrying out my invention instead of providing the radiator with a single air-outlet through which all of the air must escape 45 or be drawn out I provide the radiator with a series of air-outlets located on different sections of the radiator and employ suitable valve devices for controlling these outlets, so that the air may be permitted to escape from 50 or to be drawn out of a greater or less portion of the radiator, according to the degree

of temperature desired. By a proper operation of these valve devices the air may be permitted to remain in a greater or less portion of the radiator, and as the presence of 55 this air in a portion of the radiator will prevent that portion from becoming filled with steam it is possible to control the amount of steam condensed in the radiator and the resulting temperature, as only that portion of 60 the radiator from which the air is discharged will become filled with steam and fully heated up. The extent of the area of the radiator which is thus prevented from becoming filled with steam and heated up may be varied by 65 properly controlling the air-outlets, and thus the temperature of the radiator may be regulated.

I shall now refer to the accompanying drawings.

70 Figure 1 is a front elevation of a radiator embodying my invention. Fig. 2 is a vertical sectional view on the line *x x* of Fig. 1. Fig. 3 is a front elevation of a portion of a radiator, illustrating a modification; and Fig. 75 4 is a longitudinal horizontal sectional view on the line *y y* of Fig. 3.

75 A is an ordinary radiator made up of sections *A'*, communicating at the base in the usual manner.

80 B is the usual feed-pipe communicating with the radiator for supplying steam thereto, and in the one-pipe system this feed-pipe B also acts as the return to carry off the water of condensation.

85 C is the air-pipe connected with the radiator for carrying off the air and gases therefrom, and may be connected with a suitable exhausting apparatus, such as an ejector, for the purpose of creating a partial vacuum in 90 the air-pipe, and thus drawing the air and gases out of the radiator. Instead of connecting this air-pipe C with the radiator at one point only, as is now usual, I employ a series of connections with different sections 95 of the radiator at different distances from the supply side, and by controlling these connections by suitable valves I am able to vary the point at which the air is discharged or exhausted.

100 In the construction shown in Figs. 1 and 2 the air-pipe C extends longitudinally across

the radiator and is connected therewith at different points by branch connections C' C^2 C^3 C^4 C^5 , each of which is controlled by a suitable valve D . By manipulating the valves D a greater or less portion of the radiator may be put in connection with the air-pipe C . Thus in the construction shown in Fig. 1 if the valves in the branches C^2 , C^3 , C^4 , and C^5 are closed and the valve in the branch C' opened the air will escape only from the first section of the radiator, which will consequently become filled with steam. The air in the other sections of the radiator will not escape, and remaining therein will prevent the other portions of the radiator from becoming filled with steam and fully heated, and consequently only a small portion of the radiating-surface will be effective. If the valve in the connection C^2 is opened, the air will escape from the next two sections of the radiator, which will likewise become filled with steam and correspondingly increase the effective radiating-surface. If the valve in the connection C^3 is opened, the next three sections will be freed of air, and thus the effective radiating-surface may be increased or diminished, as desired. The branch C^5 is shown connected with the outermost section of the radiator—*i. e.*, most distant from the point of supply—and consequently when the valve in that connection is opened the air may be discharged from the entire radiator, which may then become filled throughout with steam. Only one valve need be left open at a time.

In the construction shown in Figs. 3 and 4 instead of connecting the pipe C with the radiator by a series of branch connections, each provided with a valve D , I have shown a modification, in which a series of independent pipes E' E^2 E^3 E^4 E^5 lead to the different portions of the radiator from a multiple valve E in the pipe C , by means of which any one of the pipes E' to E^5 may be put in communication with the air-pipe C , so that by the operation of the single valve E the escape of the air from a greater or less portion of the radiator may be permitted, as in the construction shown in Figs. 1 and 2.

In Fig. 1 I have shown a thermostatic valve F in the air-pipe C . This is used to prevent the escape and waste of steam, and while desirable in those systems in which the air is drawn out of the radiator by a suction in the air-pipe C is not necessary to my invention.

The details of construction shown may be varied without departing from the invention.

Having now described my invention, what I claim as new, and desire to secure by Letters Patent, is as follows:

1. The combination with a steam-radiator, of an air-pipe, independent of the supply and return pipe, communicating with said radiator at a series of points at different distances from the supply-inlet, through which the air contained in said radiator may escape into said independent air-pipe from a series of independent air-outlets, and valve devices for controlling the escape of air from the radiator to said air-pipe through said series of independent points of communication therewith. 65 70

2. The combination with a steam-radiator, of an air-pipe, independent of the supply and return pipe, communicating with said radiator at a series of points at different distances from the supply-inlet, through which the air contained in said radiator may escape into said independent air-pipe from a series of independent air-outlets, valve devices for controlling the escape of air from the radiator to said air-pipe through said series of independent points of communication therewith, and a vacuum or suction creating device communicating with said independent air-pipe to create a suction or partial vacuum therein. 85 90

3. The combination with a steam-radiator, of an air-pipe, independent of the supply and return pipe, communicating with said radiator at a series of points at different distances from the supply-inlet, through which the air contained in said radiator may escape into said independent air-pipe from a series of independent air-outlets, valve devices for controlling the escape of air from the radiator to said air-pipe through said series of independent points of communication therewith, a thermostatic valve in said air-pipe, and a vacuum or suction creating device communicating with said independent air-pipe to create a suction or partial vacuum therein. 95 100

4. A steam-radiator composed of a series of upright receptacles or hollow sections communicating with one another in series at the base, a steam-supply pipe communicating with said base at one end and adapted to supply steam to all of said receptacles or sections in series, air-outlets from the end receptacles or sections of the series, independent air-outlets from intermediate sections or receptacles, and valve devices for controlling said air-outlets, whereby the escape of air from a greater or less portion of the radiator may be controlled. 105 110

In testimony of which invention I hereunto set my hand.

MEREDITH LEITCH.
